AIR LOUVER FOR HEATING OR COOLING UNITS

Henry J. Lange, Hammond, Ind., assignor to Betz Corporation, Hammond, Ind., a corporation of Indiana

Application July 15, 1946, Serial No. 683,733

3 Claims. (Cl. 257—137)

1

The present invention relates to air louvers for heating or cooling units.

The invention has particular application to heating or cooling units of the type comprising a bank of tubes or coils through which the heating or cooling medium is circulated, and on which tubes or coils are assembled sheet metal fins which serve as air directing or distributing surfaces and which also serve as thermal transfer surfaces for increasing the effective heating or cooling surfaces of the tubes.

The general object of the present invention is to provide an improved construction of air deflecting louvers which are made up as integral parts of the sheet metal fins in the manufacture of the latter. These improved air deflecting louvers are punched directly from the sheet metal fins in the form of louver tabs inclined at the desired angle to direct the air either upwardly, downwardly, or in any other desired direction.

Another object of the invention is to provide an improved construction of louver tab which is of shorter dimension along its free edge than along its base portion, whereby the louver tabs of adjacent fins can be readily nested together in the tab openings of these fins, and whereby the louvers adapt themselves either to a parallel assembly of the fins for a flat type of heating or cooling unit, or to a radial assembly of the fins for a curved or half-round type of unit.

Other objects, features and advantages of the invention will appear from the following detailed description of one preferred embodiment thereof. In the accompanying drawing illustrating such embodiment:

Figure 1 is a horizontal sectional view through the upper portion of a half-round type of cooling unit embodying my invention;

Figure 2 is a vertical transverse sectional view through such unit;

Figure 3 is a fragmentary view on a larger scale showing the relation of fins and louvers on the outer row of tubes;

Figure 4 is a fragmentary front view showing the fins and louvers viewed from the outer edges of the fins;

Figure 5 is a diagonal sectional view taken approximately on the plane of the line 5—5 of Figure 3; and

Figures 6 and 7 are fragmentary side and edge views respectively of one of the fins on a larger scale, showing in greater detail the trapezoidal proportions of the louver tab and tab opening.

In Figures 1 and 2 I have shown a more or less conventional design of half-round cooling unit

2

adapted for cooling a circulated flow of air, but it will be understood that this type of structure has been chosen merely for the purpose of showing one typical or preferred adaptation of my invention, and that the invention can also be adapted to other heating or cooling units. In this exemplary unit, the top and bottom of the unit are closed by upper and lower housing plates 10 and 11 of semi-circular outline. The straight rear edges are joined to a vertical rear wall 12, and the arcuate edges are curved inwardly at 13 to conceal the top and bottom edges of the sheet metal fins. The cooling medium is circulated through the tubes 14 which are bent into arcuate outlines corresponding to the half round contour of the unit, these tubes preferably being grouped or assembled in vertical tiers, three such tiers or vertical rows being shown. Mounted on these tubes are the sheet metal fins 16 and 17 which direct the air radially outwardly from the unit, and which also serve to increase the effective surface area through which the tubes exert their cooling influence on the air. These fins have openings punched therein through which the tubes are passed, the fins being threaded over the tubes prior to the establishment of the coupled connections at the ends of the tubes. Air is circulated through the unit by a fan 19 revolving within an air intake opening 21 formed in the lower wall 11 of the housing. This fan is driven by an electric motor 22 which is supported in any suitable mounting bracket 23, preferably attached to the top wall 10 of the housing. The fan functions to draw air upwardly through the intake opening 21 and to impel the air outwardly through the multiplicity of spaces between the horizontal rows of tubes 14 and between the vertically spaced fins 16 and 17.

The louvers which constitute the fundamental feature of the present invention are shown at 25. These louvers consist of tabs or vanes which are punched directly out of the sheet metal fins 17. Preferably, in the half-round type of unit the outer tier of tubes 14 is provided with separate fins 17, independent of the fins 16 mounted on the inner tier or tiers of tubes, and the louver tabs are preferably formed only in these outer fins 17. However, if desired, similar louver tabs might also be punched in the inner fins 16, 15. These louver tabs or vanes are inclined at the appropriate angle to direct the air in the desired direction, i. e., if it is desired that a substantial part of the air be deflected in an upward direction, these louver tabs are inclined substantially at the upward angle shown, whereas if it is de-

sired that the air be deflected downwardly, then these louver tabs would be inclined reversely so as to deflect the air downwardly. The punching of the tabs or tongues can be performed as a single punching and bending operation, wherein the punch pierces or cuts the metal around three edges of the tab, and then bends the tab laterally into a position projecting substantially at right angles to the plane of the fin. Of course, the outward bending of the tab 25 leaves an opening 28 of corresponding outline in the sheet metal stock, which opening I shall term the tab opening. Each tab 25 and its opening 28 are of approximately trapezoidal outline, with the free edge 25' of the tab of shorter dimension than the base portion 25'' of the tab. Correspondingly, this leaves the edge 28' of the opening 28 of shorter dimension than the opposite edge 28''. This trapezoidal outline of the tabs and of the openings enables the tabs to be nested together, with the tabs extending into the openings in adjacent fins, as shown in Figure 5. The overlapped relation of the tabs produces a continuous louver structure without any break in its continuity from end to end of the cooling or heating unit. This overlapped relation of the tabs, and the ability of the tabs to slide inwardly and outwardly of the openings 28 in adjacent fins, affords a very desirable latitude of assembly because the fins can be assembled in parallel relation for a flat type of unit, or they can be assembled in radial relation for a curved or half-round type of unit, without in any way interfering with the functional relation of the louver tabs.

Each fin is also punched with the necessary holes 28 for receiving the tubes 14. Each hole 28 is preferably formed with an annular lip or flange 29 projecting laterally from the sheet metal fin. This flange 29 increases the metal-to-metal contact between the fin and each tube. These flanges also act as spacers for spacing the inner edge portions of the fins at a substantially predetermined distance from each other. Said flanges are of less height or lateral projection than the louver tabs 25, so that with the fins assembled at the lateral spacing substantially predetermined by the circular flanges 29, the louver tabs 25 will still project into the openings 28 of the next adjacent fins and establish the overlapping relation of adjacent tabs. As shown in Figure 3, the louver tabs are preferably located where they will act most effectively on that portion of the air stream flowing horizontally between pairs of tubes 14. In the upwardly inclined relation of the tabs the lower edges of the tabs are approximately in such relation to the tubes 14 that a considerable part of any moisture collecting on the tabs can drain back onto the surfaces of the tubes. The fins are preferably stamped out of sheet aluminum, but may be made of other metal if desired.

For a flat type of heating or cooling unit where the tubes 14 extend in straight line relation back and forth across the unit, the fins 17 can be punched out identically as described above for the half-round type of unit. Figure 3 might be considered to be a transverse section through such a flat type. As an alternative construction for the flat type of unit, the fins may be made considerably wider, corresponding to the fins 16, 16 and 17 of Figure 3 being made all in one piece.

The invention has utility in heating units as well as in cooling units, and accordingly in the appended claims I have used the expressions "thermal exchange unit" and "thermal exchange tubes" to cover both types of construction.

While I have illustrated and described what I regard to be the preferred embodiment of my invention, nevertheless it will be understood that such is merely exemplary and that numerous modifications and rearrangements may be made therein without departing from the essence of the invention.

I claim:

1. In a thermal exchange unit of half-round type including a housing comprising spaced upper and lower plates of semi-circular form, a bank of heat transfer tubes curved in semi-circular outline and disposed between said upper and lower plates, an air intake opening in one of said plates, 10 a fan rotating approximately in said opening for drawing air into the space between said plates and forcing it outwardly between said tubes, an electric motor connected to drive said fan, and a plurality of sheet metal fins having apertures 15 with laterally projecting flanges, said fins being assembled over said bank of tubes with said fins disposed substantially radially of the unit and said flanges spacing the adjacent fins; means for directing the flow of said air forced outwardly between said tubes and said fins comprising louver tabs of trapezoidal outline punched out of said fins leaving correspondingly shaped openings in said fins, said louver tabs projecting laterally from their respective fins and extending into 20 the tab openings of the next adjacent fins, whereby to form a substantially continuous louver around the air discharge opening of said unit.

2. A cooling unit comprising a plurality of tubes for receiving a coolant therein, said tubes being curved in semi-circular outline and being spaced one above the other to form a cylindrical bank, means on the concave side of said cylindrical bank for circulating air through said cylindrical bank and discharging the same on the convex side thereof, a plurality of sheet metal fins having apertures therein in which said tubes are positioned, said fins being spaced with respect to each other and extending radially of said cylindrical bank of tubes, and louver tabs punched out 35 of said fins on the side of said cylindrical bank from which the air is discharged forming openings in said fins, said louver tabs being inclined upwardly and extending from their respective fins with end portions thereof extending into openings 40 in the next adjacent fins, to thereby form a plurality of substantially continuous upwardly inclined louvers positioned in the path of the air discharged through said bank of tubes for directing the discharged air in an upward direction.

3. A cooling unit comprising a plurality of tubes for receiving a coolant with said tubes being spaced one above the other to form a bank, means on one side of said bank for circulating air through said bank and discharging the same 45 on the opposite side thereof, a plurality of sheet metal fins having apertures therein in which said tubes are positioned, said fins being spaced with respect to each other and extending substantially perpendicular to said tubes of said bank, and louver tabs punched out of said fins on the side of said bank from which the air is discharged, said louver tabs being inclined upwardly and extending from their respective fins toward the adjacent fins to form a substantially continuous louver 50 positioned in the path of the air discharged through said bank of tubes for directing the discharged air in an upward direction.
